UNITED STATES PATENT OFFICE.

CHARLES B. RUSSELL, OF BROCKTON, MASSACHUSETTS.

MAGNETIC INTENSIFIER.

1,355,622.

Specification of Letters Patent.

Patented Oct. 12, 1920.

Application filed August 15, 1919. Serial No. 317,820.

To all whom it may concern:

Be it known that I, CHARLES B. RUSSELL, a citizen of the United States, and a resident of Brockton, Massachusetts, whose post-office address is No. 508 Kennedy Building, Brockton, Massachusetts, have invented an Improvement in Magnetic Intensifiers, of which the following description, in connection with the accompanying drawings, is a specification, like letters on the drawings representing like parts.

My present invention relates to motors, and more particularly to a magnetic intensifier or electric motor of the reciprocating type in which a plurality of impulses or strokes caused by the successive attraction of a plurality of armatures is utilized to impart a comparatively long stroke to a piston or other power member.

20 In electro-gravitating motors the imparting of energy to the system of moving weights to assist said weights in accomplishing their function, is essential to a proper functioning of the motor. To successfully accomplish the results desired, it is essential that the motor be quick acting through a relatively long stroke, and as the ordinary electric reciprocating motor is incapable of any but an extremely short stroke, I employ 25 the cumulative effect of the short strokes of a plurality of superposed armatures, each armature being brought successively into position for maximum effective movement.

An object of my invention therefore is an 30 improved magnetic intensifier or reciprocating motor of long stroke.

Another object of my invention is the provision of means in a device of the above-described type in which the plurality of 35 armatures are held out of engagement with each other and which are successively brought into operative relation with energized electro-magnets.

Other objects will appear as the description 40 of the invention progresses.

In the accompanying drawings illustrating the preferred embodiment of my invention,

Figure 1 is a plan view,

Fig. 2 is a side elevation,

Fig. 3 is an end elevation,

Fig. 4 is a detail, supplementing the showing in Fig. 2,

Fig. 5 is a detail of the connection between the armatures and the piston, and

Figs. 6 and 7 are views, in plan and elevation respectively, of the armature holders.

In the drawings, 10 designates a base plate of suitable material, as aluminum or brass and which may be made of the shape 60 and size, comparatively, shown to the left of the dotted line 30 in the drawings, or of the same width but twice, three times, etc., the length shown, should it be desired to mount two, three, or more of the devices 65 on the same piston, or extension thereof. The main portion of the base is rectangular in shape and extending outwardly therefrom at one end is the bearing plate 11, bearings 12, at both sides thereof, being formed 70 integral therewith. The main portion and extension 11 are provided with holes 13 through which screws or bolts pass for attaching the base in position on the gravitating motor referred to above.

Integral with the base and near one end thereof, is a transverse plate 14, on which is mounted, by bolts 15, the electro-magnets 16. Four of these magnets are shown, and I find these sufficient for the purpose, but it is obvious I may increase or diminish the number employed without departing from the spirit of the invention. Binding posts 17 on the base adjacent the plate 14 are provided for connecting the magnets 16 in a 80 suitable electric circuit. At the end of the main portion of the base 10 remote from the plate 14 is a second plate or bearing member 18 lying transversely of the base and parallel to plate 14. A bearing 19 is mounted in said plate 18 and is in alignment with a bearing 20 located in the plate 14. Mounted for reciprocating movement in the bearings 19 and 20 and parallel to the axes of the electro-magnets 16 is a piston 21, as 85 clearly shown in Figs. 1, 2 and 3.

Mounted on the piston 21 and rigidly secured thereto by the pin 22 is sleeve 23, this sleeve being provided with the plurality of steps 24 of equal length but different diameters, as clearly shown in Fig. 5. Slidably mounted on the steps 24 are the armature holders 25, one holder for each of the steps 24, and each holder being a free sliding fit on its associated step. On each end of the holders is a notch 26 which slidably engages with the rod 27, attached at each end of the plate 18, by bolts 28, the rods 27 holding the plurality of holders in alignment. At one end of the central portion of 95 100 105 110

the holders 25 are perforations 29, three in number, in which are driven pins 31, and, referring particularly to Fig. 1, it will be seen that the outer pins on the holder adjacent the magnets 16, are engaged by the ends of the spring 32, while the center pin of the second holder is engaged by the middle of the spring 32. This arrangement is continued throughout the series of 10 holders shown, and the springs are so proportioned that the holders are held out of engagement with each other. The holders 25 are of any suitable non-magnetic material, as brass or aluminum, except the one 15 remote from the magnets 16, which one is made of a good quality of magnetic material, as soft iron. Attached to the holders 25 at the ends of the central portion thereof are armatures 33 of suitable magnetic material. These armatures are so mounted as 20 to be in alinement with a vertical pair of the magnets 16, as clearly shown in Fig. 1. The purpose of making the last or outer holder 25 of magnetic material is for completing 25 the magnetic circuit when all the armatures are fully attracted.

Rotatably mounted in the bearings 12 is the shaft 34 having attached to the central portion thereof the crank 35.

30 Pivottally attached to the outer end of the crank is one end of the link 36, the other end of which is pivotally attached to the cross-head 37 securely fastened to the end of the piston 21. A crank 38 mounted 35 on one end of the shaft 34 has pivotally mounted at its outer end the connecting rod 39, and through which power is transmitted from the motor above described to any suitable mechanism. At the other end of 40 the shaft 34 is attached the boss 40 having a lateral projection 41, to which is attached the threaded end of the rod 42, the nut 43 acting as the lock nut to securely hold the rod 42 in position. Adjustably mounted on 45 the rod 42, by the bolt 44, is the weight 45. As power is transmitted from the motor during the downward movement of the piston 21, the weight 45 assists in giving to the piston the quick, sharp movement that 50 aids the motor in accomplishing its function.

The operation is as follows: assuming that but a single series of the holders shown to left of Fig. 1 are involved and that all 55 parts are in the position therein shown, the circuit through the electro-magnets 16 is completed by any suitable means. The electro-magnets 16 attract the armatures 33 on the holder 25 adjacent their pole ends, 60 the remaining holders and attached armatures following as a matter of course being assisted in such movement and retained in relative position with respect to the first said holder and armatures by the springs 65 32. This downward movement, or move-

ment toward the electro-magnets 16 is assisted by the weight 45. Immediately the first pair of armatures engages with the pole ends of the electro-magnets 16, the circuit through such magnets remaining closed, 70 the second pair of armatures is attracted, followed by the third, etc., in succession, until when the last pair is attracted, the magnetic circuit is completed, because of the fact that the last holder 25 is composed 75 of magnetic material. As the first pair of armatures are associated with the pole ends of the electro-magnets to obtain maximum efficiency, and as each succeeding pair are moved with the first pair as a unit, and successively into position to obtain maximum efficiency, it will be seen that each pair of armatures imparts what practically amounts to a sharp blow to the piston 21, and that the rapid succession of such blows 80 85 moves the piston through a comparatively long distance, the result being that I obtain an efficient long stroke motor.

If more power is desired than that obtained from a single series of pairs of armatures 25 and associated electro-magnets 16, 90 I may lengthen the base 10 by adding the portion 46, as described above and placing thereon a second series of pairs of armatures 25 and associated electro-magnets 16, 95 coupling the piston extension 47 to the piston 21 by the coupling 48, the sets of electro-magnets 16 being then connected in series to attract the related pairs of armatures 33 on the sleeves 23 simultaneously. 100

While I have described the preferred embodiment of my invention somewhat in detail, it is to be understood that I may vary the size, shape and arrangement of parts herein shown within comparatively wide 105 limits, without departing from the spirit of the invention.

Having thus described my invention, what I claim as new and desire to secure by Letters Patent, is;

1. In a device of the class described, the combination of an electromagnet, a plurality of armatures associated therewith and spaced apart therefrom and from each other, means for bringing each succeeding armature into operative relation with said electromagnet as the preceding armature is attracted, and means for completing the magnetic circuit for the electromagnet only upon the attraction of the last of the plurality of armatures. 110

2. In a device of the class described, the combination of a plurality of electromagnets arranged in pairs, a piston, arranged parallel to the axes thereof and slideable 12 longitudinally with respect thereto, a stepped sleeve mounted on said piston, a plurality of holders, one for each step of the sleeve, slidably mounted thereon, a pair of armatures mounted on each of said 13

holders, one armature of each pair being in alinement with each other and with the axes of the pairs of electromagnets, and yielding means for holding each holder and 5 associated armatures in operative relation with, but out of engagement with, each other, whereby the relative position of the armatures is maintained as they are successively attracted by the electromagnets.

10 3. In a device of the class described, the combination of a plurality of sets of electromagnets connected in series, a plurality of sets of armatures, one for each set of electromagnets, a piston common to the sets of 15 electromagnets and armatures, the corresponding armatures of each set of armatures

being connected to the piston for simultaneous action thereon, and means for holding the armatures of each set out of engagement with each other and for bringing the 20 same to be brought into operative relation successively, whereby the piston is moved through a relatively long stroke by a succession of impulses.

In testimony whereof, I have signed my 25 name to this specification, in the presence of two subscribing witnesses.

CHARLES B. RUSSELL.
